UNITED STATES PATENT OFFICE

CARL LAWRENCE MATTISON, OF ROCKFORD, ILLINOIS, ASSIGNOR TO MATTISON MACHINE WORKS, OF ROCKFORD, ILLINOIS, A CORPORATION OF ILLINOIS

CONVEYER PAD

Application filed July 9, 1928. Serial No. 121,327.

This invention pertains to conveyer pads and particularly to moulded rubber pads which are adapted to be replaceably secured in prearranged relation to each other on an endless conveyer for a woodworking machine such as a sander.

In machines of this type it is an essential feature that the conveyer, which feeds the work into position to be operated on, holds the work so that there is a minimum of lateral displacement either longitudinally or transversely of the direction of travel of the conveyer. It is also desirable to provide the conveyer with a surface which will have a slight yielding action tending to force the work into engagement with the drums. Rubber, in various forms has been used for this purpose, but heretofore difficulty has been encountered in providing a surface of rubber which would serve the purpose and at the same time would not entail great expense in replacement or repair if the surface became torn or damaged. It is the general object of this invention to provide a new and improved pad for a conveyer adapted to be one of a number of such pads which constitute the surface of the conveyer and which may be readily and easily replaced if damaged.

Another object of this invention is to provide an improved conveyer pad which may be manufactured at a low cost, is readily replaceable, and is efficient in operation.

Another object is to provide an improved surface for a conveyer which comprises a plurality of separate pads removably secured to the base of the conveyer.

A further object is to produce a conveyer in which the contact surface is composed of a plurality of right and left hand pads constructed to provide a definite pattern or tread.

Another object is to provide a conveyer pad which has a regular shape so that the

pads may be placed in abutting relation to each other.

Another object is to produce a conveyer pad which has a resilient surface formed to provide a series of members which are adapted to contact the work.

Other objects and advantages will be apparent from the following description and the accompanying drawings, in which:

Fig. 1 is a fragmentary plan view of a conveyer illustrating the improved form of the invention.

Fig. 2 is a section taken on the line 2—2 of Fig. 1.

Fig. 3 is a section taken on the line 3—3 of Fig. 1.

Fig. 4 is an enlarged plan view of the preferred form of the invention.

Fig. 5 is a section taken on the line 5—5 of Fig. 4.

While I have shown in the drawings and will hereinafter disclose in detail the preferred embodiment of the invention, it is contemplated that various changes in construction and arrangement may be made by those skilled in the art without departing from the spirit and scope of the invention as expressed in the appended claims.

In the type of conveyer contemplated by this invention, a traveling bed is adapted to receive a plurality of individual pads which provide the bearing or contact surface of the conveyer. The traveling bed comprises the usual pair of heavy endless chains having links 10 to each of which a cross bar 12 is secured, as by means of bolts 11. The chain may be of any construction suitable to that particular type of machine in which the conveyer is to be used, while cross bars 12 are preferably formed of sufficiently heavy steel to prevent any possibility of their springing intermediate the two chains.

The pad 13 in its preferred form (Figs. 4 and 5) comprises a suitably heavy metal base 14 provided with a resilient surface 15.

on one side thereof. The flexible surface is usually formed of rubber which is moulded on and vulcanized to the metal base 14. In order firmly to secure the rubber surface 15 to the base 14 a plurality of openings 16 are provided in the base, said openings being countersunk from the under side of the base as shown in Fig. 5. Thus when the rubber surface 15 is moulded on the base 14 the rubber will enter the openings 16 and provide a wedge shaped foundation which upon vulcanization will resist any force tending to pull, tear or shear the rubber surface from the base.

15 An important part of this invention is the form of the contact surface of the pad and the pattern or tread which is formed by these pads when they are secured to the bars 12. The pad 13 is preferably in the form 20 of a parallelogram and the contact or bearing surface of each pad, after moulding, presents a series of alternating ridges 17 and grooves 18, said ridges and grooves running parallel to one side of the pad. Each 25 pad is secured on the bar 12, as by means of headed bolts 19 threaded into holes in the bars 20 through apertures in the rubber surface and countersunk openings 21 in the base 14 of the pad, in such position that the 30 ridges 17 and grooves 18 will be at an angle with the edges of the bars 12.

Inasmuch as a transverse creeping motion would be imparted to the work if the ridges 17 on every pad were to run in the same 35 direction, right and left hand pads have been provided. That is to say, the pads are similar in general shape and contour but are reversely formed so that if the backs of a right hand and a left hand pad are placed 40 together the margins of the pads will coincide. These right and left hand pads are secured upon the alternating bars of the conveyer, that is, the right hand pads are fastened to every other bar and the left hand 45 pads are rigid with the intervening bars. In this manner an irregular zig-zag tread is formed on the contact surface of the conveyer.

It is, of course, obvious that the ridges 50 may run in an unbroken line, but it has been found preferable to stagger the ridges and the grooves on adjacent bars. In other words, when the pads are properly secured on the bars 12, the ends of the ridges 17 on 55 the pads on one bar will be opposite the grooves 18 on the pads on the adjacent bar. As the right and left hand pads are the same size the proper positioning of the pads on the bars to obtain the staggered relation is 60 a simple matter of predetermining the position of the bolt holes 20 in the bars 12.

Due to the non-rectangular shape of the pads 13, spaces, each in the shape of a trapezoid, will be left at each end of the bars 12. 65 These spaces may be covered by specially

moulded pads, or the overhanging ends of a regular pad may be cut off.

It will be readily apparent from the foregoing disclosure that a pad has been provided which is very simple in structure and which will be strongly resistant to a force tending to separate the rubber from the supporting base. Moreover, a pad has been provided which may be easily replaced in the conveyer when damaged or worn, without disturbing the adjacent pads.

As shown plainly in Figs. 2 and 3, it will be impossible for any metallic part to contact or bear against the work until after the tread has been almost entirely worn away. Injury to the work can thus be avoided, since the worn pads can be replaced before the tread is entirely worn away.

Furthermore, a conveyer has been devised 85 which has a resilient bearing surface and which, due to the design of the tread, will resist any tendency of the work to creep.

I claim as my invention:

1. A conveyer pad, comprising, in combination, a parallelogrammic base having a 90 plurality of openings therein, a resilient surface on one side of said base, having parts thereof entering said openings to anchor said surface on said base, and a plurality of ridges on said surface extending substantially 95 parallel to one side thereof.

2. A conveyer having in combination, supporting means, similarly shaped but reversely formed replaceable pads arranged on said supporting means to provide a surface for 100 said conveyer, each of said pads comprising a base having a resilient surface, said surfaces having a plurality of ridges thereon at an angle to the direction of travel of said conveyer.

3. In a conveyer comprising, in combination, a traveling bed including a plurality of cross bars, a plurality of pads secured on each of said cross bars and arranged to provide a continuous contact surface for 110 said conveyer, said surface of each of said pads being formed of a resilient material having a plurality of ridges thereon extending at an angle to the direction of travel of said conveyer, the angles of said ridges on longitudinally adjacent pads being in opposite directions to form a zigzag tread extending longitudinally of the conveyer.

4. In a conveyer comprising, in combination, a traveling bed including a plurality of cross bars, a plurality of similarly shaped but reversely formed pads arranged on said bed to provide a contact surface for said conveyer, each of said pads having a flexible surface including a series of ridges extending angularly thereacross, said right hand pads being secured to alternate bars and said left hand pads being secured to the intermediate bars in such position that the ridges provide a zig-zag tread for the conveyor.

5. A conveyor having, in combination, a traveling bed including a plurality of cross members, a plurality of pads secured to alternate members, and a plurality of similar
5 but reversely shaped pads secured to the intermediate members, the surfaces of said pads being formed with ridges, said pads being positioned on said bars so that the ridges on one group of pads will be staggered in
10 relation to the ridges on the group of pads on the adjacent bars.

In testimony whereof I have hereunto
affixed my signature.

CARL LAWRENCE MATTISON.
